UNITED STATES PATENT OFFICE.

ELMER J. SMITH, OF DETROIT, MICHIGAN, ASSIGNOR TO PETER SMITH HEATER COMPANY, OF DETROIT, MICHIGAN, A COPARTNERSHIP.

HEATING APPARATUS.

1,016,969.

Specification of Letters Patent. Patented Feb. 13, 1912.

Application filed March 13, 1909. Serial No. 483,242.

To all whom it may concern:

Be it known that I, ELMER J. SMITH, a citizen of the United States of America, residing at Detroit, in the county of Wayne and State of Michigan, have invented certain new and useful Improvements in Heating Apparatus, of which the following is a specification, reference being had therein to the accompanying drawings.

10 The invention relates particularly to a hot air heating apparatus, especially designed for use in connection with street railway cars, and consists in the novel construction of the apparatus, in the peculiar arrangement and combination of its parts, and in certain details of construction, as will be more fully hereinafter set forth.

In the drawings,—Figure 1 is a horizontal section through a railway car of ordinary construction, illustrating the heating apparatus diagrammatically; and Figs. 2 and 3 are sectional perspective views of the generator.

15 In the drawings thus briefly described, A represents a car of usual construction, provided with seats B extending along each side thereof, and the ordinary front vestibule C.

D represents the generator of the apparatus, located within the vestibule and resting upon the flooring E thereof.

20 F is a system of pipes leading from the generator within the interior of the car and extending preferably beneath a forward seat, as G.

25 H is a fan for producing a force draft through the system of piping, and I is a motor for and located with the fan beneath the seat referred to.

30 J represents the main conveyer pipe or conduit leading from the generator and extending along one side of the car beneath the seats, and provided with a number of openings or outlets, as J', through which the hot air is discharged within the car interior.

The generator referred to is composed of an outer metallic casing K, preferably square in configuration, provided with a flooring L and a hollow base section M. The flooring 35 is formed with a plurality of ports, as O, arranged preferably one in each corner, as indicated in Fig. 2, these ports constituting air inlets, and the car flooring L has an opening P formed therein preferably centrally 40 in relation to the flooring L, forming an in-

let to the interior of the casing for the external air.

Q designates an inner casing, preferably circular in form, mounted upon a lateral flange or shoulder R on the heater proper R'. I have preferably shown the heater in the form of a stove, provided at its lower portion with a box, as S, that projects forwardly through the outer drum or casing, and is provided with fuel and ash doors T and U respectively.

V represents the ordinary smoke pipe for the stove, extending through both casings and adapted to project outwardly through the roof of the car.

25 The casings described being positioned one within the other form between them an outer air chamber, as W (Fig. 2), and an inner chamber, as X, these chambers being differentially heated by the heater proper within the inner casing.

30 Y represents a pipe entering the lower portion of the outer casing at a point Z constituting the casing inlet, and rising vertically within said casing to near the top thereof, the upper end of the pipe being open. This pipe extends from the generator, as indicated in Fig. 1, to the fan casing A'. B' represents a similar pipe leading from the fan casing within the air chamber 35 W of the generator and extending upwardly thereto a point above the top of the casing Q, and then downwardly within said casing into communication with the air chamber X.

35 The main conveyer pipe or conduit J leads 40 outwardly from the lower portion of the air chamber X, and as before stated passes along the side of the car, where it is adapted to discharge the hot air through the several openings therein within the car interior.

45 In the operation of the apparatus, the blower fan causes air from outside the car to enter the chamber W through the ports P and O, to pass vertically within said chamber and to discharge therefrom through the pipe Y into the fan casing. The air is then driven through the pipe B' into the upper part of the chamber X, and is forced 50 downwardly therethrough and outwardly within the main conveyer pipe J, from 55 which it enters the car.

55 As thus constructed, it will be seen that pure outside air is first drawn within the generator and partially heated, and again 60 passed through the generator and finally 65

heated before it is discharged within the interior of the car, thereby increasing the heating efficiency of the apparatus. Further, the various parts of the heating mechanism are so arranged within the car as to occupy no more available space than the apparatus now ordinarily in use.

A slide A² is preferably formed in the wall of the outer casing opposite the partition separating the vestibule from the car proper, the slide opening being adapted to register with the usual air discharge opening formed in the partition. By opening the slide, and thereby establishing communication between the outside air chamber of the heater and the car interior, the heating apparatus may be used as an ordinary heater, and this is desirable when the fan is at rest, as where the car is in the barn. When the forced draft is eliminated, the air passes merely through the outer air chamber, where it is heated by the jacketed stove, the heated air being discharged directly within the car interior.

25 What I claim as my invention is,—

1. A car heater of the character described comprising a heater, a casing surrounding said heater spaced from the top and sides thereof to form a substantially closed heating chamber therebetween, a second casing surrounding said first mentioned casing and spaced from the top and sides thereof to provide a preliminary heating chamber, said last named chamber being provided with an inlet in its lower portion for fresh air, means

for positively withdrawing the preliminarily heated air from the upper portion of said preliminary heating chamber and for forcing said air downwardly through the first mentioned heating chamber, and an outlet from the bottom portion of the latter leading beyond the preliminary heating chamber and adapted to discharge into a conduit therewithout at a point adjacent to the floor of the car.

2. A car heater of the character described comprising a heater, a casing surrounding said heater and spaced from the top and sides thereof to form a substantially closed heating chamber therebetween, a second casing surrounding said first mentioned casing and spaced from the top and sides thereof to provide a preliminary heating chamber, said last named chamber being provided with an inlet in its lower portion for fresh air, means for positively withdrawing the preliminarily heated air from the upper portion of said preliminary heating chamber and for forcing said air downwardly through the first mentioned heating chamber said first mentioned heating chamber having an outlet for heated air in the lower portion thereof.

In testimony whereof I affix my signature in presence of two witnesses.

ELMER J. SMITH.
